US00D852259S

(12) **United States Design Patent** (10) Patent No.: **US D852,259 S**
(45) Date of Patent: **** Jun. 25, 2019**

(54) **CAMERA HOUSING**

(71) Applicant: **GoPro, Inc.**, San Mateo, CA (US)

(72) Inventors: **Richard Goscia**, Santa Clara, CA (US); **Seunghon Lee**, Cupertino, CA (US); **Derek Yap**, San Carlos, CA (US); **Evan L. Coons**, San Mateo, CA (US); **Joshua P. Davies**, Fremont, CA (US)

(73) Assignee: **GoPro, Inc.**, San Mateo, CA (US)

(**) Term: **15 Years**

(21) Appl. No.: **29/654,195**

(22) Filed: **Jun. 21, 2018**

Related U.S. Application Data

(63) Continuation of application No. 29/588,383, filed on Dec. 20, 2016, now Pat. No. Des. 821,481, which is a continuation of application No. 29/557,076, filed on Mar. 4, 2016, now Pat. No. Des. 778,336, which is a continuation of application No. 29/516,749, filed on Feb. 5, 2015, now Pat. No. Des. 751,133, which is a continuation of application No. 29/491,394, filed on May 20, 2014, now Pat. No. Des. 725,169, which is a continuation of application No. 29/461,140, filed on Jul. 18, 2013, now Pat. No. Des. 710,921.

CLAIM

The ornamental design for a camera housing, as shown and described.

DESCRIPTION

FIG. 1 is a front, top and right side perspective view of a camera housing showing our new design;

FIG. 2 is a front, bottom and left side perspective view thereof;

FIG. 3 is a rear, bottom and right side perspective view thereof;

FIG. 4 is a rear, bottom and left side perspective view thereof;

FIG. 5 is a front elevational view thereof;

FIG. 6 is a rear elevational view thereof;

FIG. 7 is a left side elevational view thereof;

FIG. 8 is a right side elevational view thereof;

FIG. 9 is a top plan view thereof; and,

FIG. 10 is a bottom plan view thereof.

The broken lines in the drawings represent unclaimed subject matter of the camera housing and form no part of the claimed design.

1 Claim, 10 Drawing Sheets
